UNITED STATES PATENT OFFICE.

AUGUST WEBER, SR., OF SCHENECTADY, NEW YORK.

INCANDESCENT-ELECTRIC-LAMP SOCKET.

SPECIFICATION forming part of Letters Patent No. 743,306, dated November 3, 1903.

Application filed December 10, 1902. Serial No. 134,608. (No model.)

To all whom it may concern:

Be it known that I, AUGUST WEBER, Sr., a citizen of the United States, residing at Schenectady, county of Schenectady, and State of New York, have invented certain new and useful Improvements in Incandescent-Electric-Lamp Sockets, of which the following is a specification.

The invention relates to such improvements; and it consists of the novel construction and combination of parts hereinafter described and subsequently claimed.

Reference may be had to the accompanying drawings, and the reference characters marked thereon, which form a part of this specification.

Similar characters refer to similar parts in the several figures.

Figure 1 of the drawings is a view, partly in side elevation and partly in central vertical section, of a key-socket for incandescent electric lamps embodying my invention. Fig. 2 is a view in side elevation of the same with the cap removed and showing the handle end 25 of the key. Fig. 3 is a view, partly in side elevation and partly in central vertical section, of a keyless socket embodying my invention.

The principal object of my invention is to provide a simple and effective automatically-locking connection between the sleeve and cap of an incandescent-electric-lamp socket.

Other objects of the invention will appear in connection with the following description.

My invention is applicable to various telescopically-connecting members, but is especially adapted for use in the telescopically-connecting cap and sleeve members of incandescent-electric-lamp sockets, and I have illustrated in the drawings its use in such connection.

In carrying out the principal feature of the invention the inner telescoping member is made compressible, and the telescopically-connecting members are provided, in the manner hereinafter described, with interengaging parts adapted to automatically interlock with a snap action when telescopically applied to each other and to be released by compression 5c of said inner member.

Referring to Figs. 1 and 2 of the drawings, 1 is the sleeve member, and 2 the cap mem-

ber, of the case of a key-socket for incandescent electric lamps, both of said members being preferably formed of resilient sheet metal. 53 The case thus formed is adapted to contain the insulating-base 3, upon which is mounted the screw-socket 4, fixedly connected therewith and adapted to receive the screw-threaded shank of an incandescent electric lamp, 60 and the key 5, rotary in the hanger-bearing 6, operatively connected with the switch-block 7, adapted to make and break connection between the metal screw-socket 4, which connects with one of the lamp-terminals, and 65 the spring 8, having a connection (not shown) with one of the circuit-wires 9, the other of the circuit-wires 9 having a connection (not shown) with the spring-arm 10, projecting interiorly of the screw-socket through an aperture 11 in the wall thereof and adapted to contact with the other lamp-terminal, all in the usual well-known manner. 70

I have not shown in detail the construction of the switch mechanism nor such parts of 75 the electrical connections as are concealed in the base 3, the manner of constructing and connecting such parts being well known to those skilled in the art.

The insulating-base 3 is made to fit loosely 80 within the sleeve 1, which is made compressible by means of the slot 12, formed in the inner end thereof to receive the shaft of the key 5. On opposite sides of this slot are formed projections 14 on the exterior of the 85 sleeve near its inner end, as by slitting the sheet metal at right angles to the slot 12 and forcing outwardly a portion of the metal shell on the inner side of such slit, the projection thus formed terminating abruptly at its outer 90 end at said slit and inclining inwardly therefrom toward the inner end of the sleeve, as shown.

The cap 2 is provided with apertures 13, arranged to correspond with the position of 95 the projections 14 and adapted to receive said projections, respectively, when the parts are telescopically applied to each other. The sleeve being compressible and said projections beveled or inclined from the inner end 100 of the sleeve toward their outer ends, whereas they terminate abruptly, the cap can be telescopically applied to the slotted end of the sleeve, and when the apertures 13 in the cap

are brought opposite the respective projections 14 on the sleeve the parts will automatically interlock with a snap action. The abruptly-terminating ends of said projections 5 effectually prevent accidental separation of the cap from the sleeve; but when it is desired to separate said members it is only necessary to compress the sleeve until said projections are withdrawn from the apertures in 10 the cap. The connected members themselves thus provide the means whereby they are locked together, dispensing with the use of screws or other additional parts for that purpose.

15 If desired, the loosely-fitting insulating-base 3 may be supported within the sleeve by means of one or more tongues 15, formed by slitting and bending inwardly portions of the sleeve-wall adapted to engage said base, which 20 may be provided with a groove or recess 16, adapted to receive the several tongues.

In Fig. 3 I have shown a keyless socket, the sleeve 17 being provided with no slot for a key, but with a narrow slot 18, adapted to render the 25 inner end of the sleeve compressible. The cap 19 is provided with inward projections 20, inclined inwardly toward and terminating abruptly at their inner ends, whereat the shell is slitted, and adapted to enter apertures 21, 30 formed in the sleeve by cutting and introverting portions thereof to form tongues 22, which enter grooves or recesses 23 in the inclosed loosely-fitting insulating-base 24 to assist in supporting the same within the sleeve 35 and to prevent rotative movement between said sleeve and base when a lamp is being inserted in or removed from the screw-socket 25, fixedly connected to said base. The screw-socket 25 and contact-arm 26 are connected 40 with the circuit-wires 9 in the usual manner, the connections being not shown. The socket-sleeve may be provided with a bushing or lining of insulating material 27.

What I claim as new, and desire to secure 45 by Letters Patent, is—

1. In a device of the class described, the combination with a pair of members comprising a sheet-metal sleeve having a slotted end and introverted tongues, and a cap adapted to telescopically receive the slotted end of 50 said sleeve, said members having interengaging parts adapted to automatically interlock with a snap action when telescopically applied to each other, and to be released by 55 compression of said sleeve; of an insulating-base for electrical fittings loosely inclosed

within said sleeve in engagement with said tongues, substantially as described.

2. In a device of the class described, the combination with a base of insulating material having a peripheral recess; and an incandescent-lamp support mounted thereon; of an inclosing case therefor comprising in part a sheet-metal sleeve having a portion of its wall introverted to occupy said base-recess, 60 substantially as described.

3. In a device of the class described, the combination with a base of insulating material having a peripheral recess; and a screw-socket fixedly mounted thereon; of an inclosing case therefor comprising in part a sheet-metal sleeve having a portion of its wall introverted to occupy said base-recess and prevent a relative rotative movement between said sleeve, base and socket, 70 substantially as described.

4. In a device of the class described, and in combination a pair of members comprising a sheet-metal sleeve having a slotted end, and a sheet-metal cap adapted to telescopically receive the slotted end of said sleeve, one of said members being provided with a recess, and the other having a correspondingly-located transverse slit and the wall on one side thereof displaced to form a projection beveled or inclined toward said recessed member and terminating abruptly at said slit, whereby said members are adapted to automatically interlock with a snap action when telescopically applied to each other, 80 and to be released by manual compression of said slotted sleeve, substantially as described.

5. In a device of the class described, the combination with a compressible sleeve having portions of its wall cut and introverted to form tongues; of an insulating-base for electrical fittings loosely inclosed within said sleeve in engagement with said tongues; and a cap having inwardly-projecting members 100 adapted to enter the apertures formed in the sleeve by the introversion of said tongues, whereby said cap and sleeve are locked together and adapted to be released by compression of said sleeve, substantially as described.

In testimony whereof I have hereunto set my hand this 3d day of December, 1902.

AUGUST WEBER, SR.

S. H. VISSCHER.

DISCLAIMER.

743,206.—*August Weber, Sr., Schenectady, N. Y.* INCANDESCENT-ELECTRIC-LAMP SOCKET. Patent dated November 3, 1903. Disclaimer filed February 25, 1920, by the assignee, *Weber Electric Company*.

Enters this disclaimer—

“To that part of the claim in said specification which is in the following words, to wit:

“2. In a device of the class described, the combination with a base of insulating material having a peripheral recess; and an incandescent-lamp support mounted thereon; of an inclosing case therefor comprising in part a sheet-metal sleeve having a portion of its wall introverted to occupy said base-recess, substantially as described.

“3. In a device of the class described, the combination with a base of insulating material having a peripheral recess; and a screw-socket fixedly mounted thereon; of an inclosing case therefor comprising in part a sheet-metal sleeve having a portion of its wall introverted to occupy said base-recess and prevent a relative rotative movement between said sleeve, base and socket, substantially as described.”
